UNITED STATES PATENT OFFICE.

BERNHARD RÖBER, OF DRESDEN, GERMANY.

STEAM-BOILER FURNACE.

SPECIFICATION forming part of Letters Patent No. 514,497, dated February 13, 1894.

Application filed December 4, 1893. Serial No. 492,754. (No model.)

To all whom it may concern:

Be it known that I, BERNHARD RÖBER, civil engineer, a subject of the Emperor of Germany, residing at Dresden, Germany, have invented certain new and useful Improvements in Furnaces and Boilers for Steam-Engines, of which the following is a specification.

One part of my invention relates more especially to the fire-box; its objects are to obtain a large heating-surface, and to protect the casing and jacket; which ends I attain by incasing the fire-box with brick-work, and surrounding it with water-tubes partly incased in the brick-work so as to protect it and be protected by it.

My improvement further consists in combining with water-tubes surrounding the fire-box and passing through the tube-sheet, other water-tubes projecting through the tube-sheet into the fire-box, below the surrounding tubes, to obtain increased heating-surface without obstructing the draft, and also to protect the bridge over which the air passes on its way to the fire tubes.

My improvement further consists in surrounding the top and sides of the fire-box with water-tubes extending through the tube-sheet into the boiler; brick-work partly incasing these tubes, and an outer jacket inclosing the brick-work, so as to leave an air-space between the brick-work and jacket through which air passes to the fire-box.

My improvements further consist in other combinations of instrumentalities hereinafter specified.

The accompanying drawings show so much, only, of apparatus embodying my improvements in the best way now known to me, as is necessary to illustrate the subject-matter herein claimed.

Some of my improvements may be used without the others and in apparatus differing somewhat in its details of construction from those herein shown. Unless otherwise indicated the parts are of usual well known construction and operation. The furnace end I term the rear, and the opposite end, the front of the apparatus.

Figure 1 represents a vertical transverse section through the apparatus, on the line 1—1, of Fig. 2, which in turn represents a vertical

section therethrough, on the line 2—2, of the preceding figure. Fig. 3 shows a transverse section on two different horizontal planes 55 through one side of the apparatus, on the line 3—3 of Fig. 2. These figures show my improvements as more especially adapted for a boiler of the locomotive type. Fig. 4 represents a vertical transverse section on the line 60 4—4 of Fig. 5, which in turn shows a vertical longitudinal section through one side of the apparatus, on the line 5—5 of Fig. 4. These figures show my improvements as embodied in a stationary boiler. Fig. 6 is a detail view 65 on an enlarged scale of one form of water tube which may be employed, and Fig. 7 is an end view thereof.

I will first describe my improvements with especial reference to Figs. 1, 2 and 3, beginning with the furnace or fire-box A, which is shown as surrounded by an inclosing casing B, of fire-brick or equivalent material, inclosed in an enveloping jacket C, far enough from the casing to leave an air-space D, between the jacket and casing. Valves, slides or dampers c, in the jacket regulate the admission of air to this space, which communicates with the fire-box so as to draw the air heated in the space into the furnace to promote combustion of the fuel, the overheating of the jacket being at the same time prevented.

Fuel is fed to the furnace by means of a feed-screw E, somewhat like that shown in Letters-Patent No. 205,428, granted to me June 25, 1878, as assignee of August L. Schultz but actuated in a different way. It is shown as operated intermittently, or with a step-by-step movement through the intervention of 90 an eccentric f, on a rotating shaft F, of the engine, sliding endwise in bearings under the fire-box and vibrating an elbow-lever F', rocking vertically on a pivot f', and actuating a pawl f², engaging with a ratchet-gear F², on 95 the shaft of the feed-screw E.

The grate-bars G are arranged lengthwise of the furnace; their ends lying below the feed-door being horizontal for a short distance and then sloping downward to the other end of the fire-box, (see Fig. 2.) The fuel is thus first fed onto the horizontal part of the grate-bars, and then slides down their inclined portion, air being admitted both above

and below the grate. The result of this organization is that the fuel accumulates or piles up on the horizontal part of the grate, where it is coked, and then slides down the inclined part in a layer of gradually diminishing thickness. Air being freely admitted at the lower end of the bars creates a bright hot flame, which aids in consuming the gases, evolved near the feed door. To aid in burning these gases, an additional air-inlet g , is provided between the air-space and furnace, some distance above the grate; the influx of air therethrough being regulated by a valve g' controlled by a gear-wheel and screw-rod G' .

15 The sides and top of the fire-box are provided with longitudinal water-tubes H , partly embedded in or surrounded on three sides by the brick-work casing, (see Fig. 1.) These tubes are double, the outer ones h , being closed at the front or feed-end, and passing through the front head of the furnace, while the rear ends are open and project through the tube-sheet I , into the boiler J , which is filled with the usual fire-tubes j . The inner 25 water-tubes h' , are open at both ends and extend from near the front end of the outer tubes h , in which they are inclosed and concentrically arranged, through the tube-sheet into the boiler; thus keeping up a rapid circulation of the water therethrough. Similar tubes h^2 , project from the boiler into the fire-box a short distance, and are likewise partially incased in fire-brick, (see Fig. 2,) thus 30 promoting circulation in the lower part of the boiler.

35 By the construction above described much additional evaporating surface is obtained, and the casing protected without interfering with access of the products of combustion to the fire-tubes of the boiler, which may be of approved locomotive type. The water-tubes, it will be observed, are arranged outside of the circle of the fire-tubes, so as not to obstruct the draft, the brick-work being correspondingly widened out or thinned at that point, which may safely be done, as the water-tubes protect it.

By employing water-tubes such as shown in Fig. 6, an improved circulation is effected. 50 As there shown, the outer or rear end of the outer tube h is closed, as it is in the arrangement shown in Fig. 2. The inner end of the inner tube h' is open, its opposite end being slightly curved and projecting into the water-space of the boiler. Partition walls h^3 are employed to form passages to the four ports or openings 1, 2, 3, 4. These partition walls meet at their inner and outer ends, and surround the ports. The passages 5 and 6, between the partitions, are in communication with the water-space of the boiler, while the passages 7 and 8 communicate with the inner tube h' . That is to say, water entering from the water-space of the boiler, enters the tube h' , through the ports 1 and 2, as shown by feathered arrows. It passes to the rear, open end of the tube h' , as shown by the ar-

rows, then takes the direction shown by the plain arrows, and enters the ports 3 and 4, passing through the tube h' out to the water-space of the boiler. The super-heated water or steam rises to the top of the tube h' , while the cooler portion of the water moves at the bottom. By this difference of temperatures, a circulation is kept up and there is great economy of heat. The fire-brick forming the bridge wall are preferably constructed and arranged as shown in Figs. 1 and 2. As there shown, there are five blocks X , provided with openings g , through which the tubes of the bridge extend. The blocks are fitted close together, and are supported on the tubes. Air enters through the openings in the blocks below the tubes, and passes over the tops of the blocks into the fire-tubes. This is an economical arrangement; it is strong and durable, and may readily be repaired.

What I claim herein as new and of my own invention is—

1. The combination substantially as hereinbefore set forth, of the boiler, the fire tubes arranged therein, a fire box communicating with the fire tubes, water tubes closed at their rear ends and surrounding the tops and sides of the fire box, and passing through the tube sheet around the ends of the fire tubes.

2. The combination, substantially as hereinbefore set forth, of the fire box, brick work incasing the fire box, water tubes closed at one end and surrounding the top and sides of the fire box, and passing through the tube sheet of the boiler, and fire tubes passing through the tube sheet and having their ends surrounded by the water tubes.

3. The combination, substantially as hereinbefore set forth, of the fire box, having brick work extending over it, and a shell arranged around the brick work, a boiler, water tubes communicating with the boiler extending over the fire box under the brick work and through the back sheet of the fire box, said water tubes being each closed at its outer end, and provided with an inner tube open at both ends, for the purpose specified.

4. The combination, substantially as hereinbefore set forth, of a fire-box, water-tubes arranged in the fire-box, and passing through the tube-sheet to the boiler, and short water-tubes projecting through the tube-sheet into the fire-box below the fire-tubes, for the purpose specified.

5. The combination, substantially as hereinbefore set forth, of a fire-box, a tube-sheet, a bridge wall, and short water-tubes leading from the water-space of the boiler and arranged under the bridge wall.

6. The combination, substantially as hereinbefore set forth, of a fire-box, a bridge wall composed of perforated blocks, water-tubes extending through the perforations of the blocks, and air-inlets through the blocks below the tubes.

7. The combination, substantially as hereinbefore set forth, of a fire-box incased in

brick-work, water-tubes surrounding the top and sides of the fire-box and partly inclosed in the brick-work, and a jacket inclosing the brick-work so as to leave an air-space through which air may pass to the fire-box, for the purpose specified.

8. The combination, substantially as hereinbefore set forth, of the fire-box, its inclosing brick-work, longitudinal water-tubes partly incased in the brick-work, a jacket inclosing the brick-work so as to leave an air-space between the jacket and brick-work, and valves regulating the admission of air through the air-space to the furnace or fire-box.

15 9. The combination, substantially as hereinbefore set forth, with a fire-box, of a series of circulating tubes, each comprising an outer tube, with one end closed, and an inner tube with both ends open, partitions between the

inner and outer tube, forming circulating passages, and ports connecting these passages with the tubes.

10. The combination, substantially as hereinbefore set forth, with the fire-box of a boiler, of water-tubes, extending from the back plate of the fire-box to the tube-sheet, each tube consisting of an outer tube, closed at one end, an inner tube open at both ends, partition walls between the inner and the outer tube, and openings in the inner tube communicating with passages formed by the walls.

In testimony whereof I have hereunto subscribed my name.

BERNHARD RÖBER.
